UNITED STATES PATENT OFFICE

152,573

DESIGN FOR A LAMP STAND

Paul Schultz, Bally, Pa.

Application June 30, 1947, Serial No. 140,013

Term of patent 3½ years

(Cl. D48—20)

To all whom it may concern:

Be it known that I, Paul Schultz, a citizen of the United States, residing at Bally, in the county of Berks and State of Pennsylvania, have invented a new, original, and ornamental Design for Lamp Stands, of which the following is a specification, reference being had to the accompanying drawing, forming part thereof.

Fig. 1 is a plan view of a lamp stand, showing my new design.

Figs. 2 and 3 are elevational views of the same, looking in the direction of the arrows 2 and 3, respectively, of Fig. 1.

The dominant features of my design reside in the portions shown in full lines.

I claim:

The ornamental design for a lamp stand, as shown and described.

PAUL SCHULTZ.
